UNITED STATES PATENT OFFICE.

WILLIAM D. SCOTT, OF MARTINS FERRY, OHIO.

VENTILATING APPARATUS.

1,090,239.

Specification of Letters Patent. Patented Mar. 17, 1914.

Application filed December 31, 1912, Serial No. 739,541. Renewed January 28, 1914. Serial No. 815,097.

To all whom it may concern:

Be it known that I, WILLIAM D. SCOTT, a citizen of the United States of America, and resident of Martins Ferry, county of Belmont, and State of Ohio, have invented certain new and useful Improvements in Ventilating Apparatus, of which the following is a specification.

This invention relates broadly to ventilating apparatus, and specifically to a fan for producing a circulation of air in mines.

The primary object of the invention is to provide a ventilating apparatus which has a maximum capacity for gathering and delivering air and which is specially adapted for forcing air throughout the passages of mines.

A further object is to structurally improve that class of fans employed for ventilating purposes, providing a device wherein the resistance offered by the air is reduced to a minimum and which, consequently, with a given driving power, possesses greatly increased efficiency.

With these and other objects in view the invention resides in the features of construction, arrangement of parts and combinations of elements which will hereinafter be exemplified, reference being had to the accompanying drawings, forming a part of this specification, in which—

Figure 1 is a view, partly in front elevation and partly in section, illustrating the invention; Fig. 2 is a central vertical transverse section through the casing; and Fig. 3 is a detail section taken on the line 3—3, Fig. 1.

Referring to said drawings, in which like designating characters distinguish like parts throughout the several views 1 indicates a rectangular casing the outer or rear face 2 of which has therein a central circular air-intake opening 3 of suitable size or area, while the front of the casing is entirely open, as shown, to permit of the free and unobstructed delivery of air. Extended centrally through the casing is a shaft 4 which is journaled in bearings 5 carried by stationary

supports 6 located in front of and at the rear of the casing. 50

Fixed upon the shaft 4 within the casing is a hub 7 having radial arms 7' upon which are mounted a plurality of fan blades 8. Each blade is substantially semi-circular in form and is disposed upright with respect to the hub and has its straight chord-like edge crossing said hub in a diagonal direction, as is clearly shown in Fig. 2. Said blades are so disposed or spaced with respect to each other that a substantially circular fan is 60 constituted thereby and located wholly within the confines of the casing.

Interposed horizontally between and bolted to adjacent portions of adjacent blades near the peripheral edges of the latter is a 65 plurality of radially inclined transverse blades 9, as is clearly shown in Fig. 2.

In operation, the rapidly rotating blades 8 produce a powerful suction for drawing air through the intake opening 3 and force said 70 air forward through the open front of the casing. In a plain rectangular or cylindrical casing, however, said blades would necessarily encounter, and would be obliged to overcome, a great resistance due to air becoming compressed between the blades and the casing walls as it is forced outward from the center. Therefore, in order to relieve the compression and to practically eliminate this resistance, and at the same time to increase the volume of air supplied by the fan, 75 means is provided for releasing the air carried to the circumference of the fan, said means including pockets 10 formed within the corners of the casing by the provision of 80 arcuately curved plates 11, each of which is attached at one end to the casing wall and at its opposite end to braces 12 mounted upon the casing walls. Said braces serve to support the rearmost ends of said plates a short 85 distance from said walls for forming entrance passages 13 through which air forced to the periphery of the blades is driven into the said pockets 10. Mounted on the outer side of the casing adjacent to the position 90 occupied by each pocket 10 and having open

communication with said pocket through an opening or passage 14 provided in the casing wall is a receptacle 15, open at its front, as shown at the right side of Fig. 1, for receiving the air from said pocket and for directing the same forward in the direction of the blast delivered directly from the blades 8.

As is obvious, the rapidly rotating fan drives the greater portion of the air directly forward in an axial direction; and such air as is forced laterally to the outer ends of the blades is caught by the transverse blades 9 and is driven through the passages 13 into the pockets 10, thence through the openings 14 into the receptacles 15, from whence it is directed forward to join with the air delivered directly from the fan, as aforesaid.

The plates 11 and those portions of the casing walls located between adjacent ends 20 of adjacent plates together constitute a substantially cylindrical chamber within which the fan operates.

The air-inlet opening 3 is concentric with the fan and chamber and is of relatively 25 less diameter. Thus, as is apparent, the air entering through said opening is received by the fan near its center, and the greater portion thereof consequently never passes to the periphery of the fan, but is delivered directly therefrom in a forward axial direction.

While I have described my invention more or less in detail, it is obvious that 35 various changes in the form and arrangement of some of the parts may be resorted to without departing from the general spirit or scope of the invention as defined in the appended claims. Hence I am not to be understood as limiting myself to the precise construction herein shown and described.

Having thus described my invention, what I claim as new, and desire to secure by Letters Patent, is—

45 1. A ventilating apparatus comprising a rotatable fan adapted for forcing air in an axial direction, a cylindrical chamber within which said fan is located, said chamber having its front end open to permit the unobstructed delivery of air from the fan and having in its rear end an air inlet opening of less diameter than the fan and concentric therewith, a plurality of air-outlet passages leading laterally from said chamber, and 55 means whereby air forced through said passages is directed forward with the air delivered directly from the fan.

2. A ventilating apparatus comprising a 60 rotatable fan adapted for forcing air in an axial direction, a cylindrical chamber within which said fan is located, said chamber having its front end open to permit the unobstructed delivery of air from the fan and

having in its rear end an air inlet opening of less diameter than the fan and concentric 65 therewith, a plurality of pockets located laterally of said chamber, air-outlet passages leading from said chamber to said pockets, and means whereby air delivered to said pockets is directed forward to join 70 with the air delivered directly from the fan.

3. A ventilating apparatus comprising a substantially rectangular casing having its front face open and having an air-inlet opening in its rear face, a rotatable fan 75 located within said casing and adapted to force air in an axial direction, arcuately curved plates disposed across the corners of said casing, forming pockets in said corners and a substantially cylindrical fan inclosing chamber, passages leading from said chamber to said pockets, and means for directing air from said pockets in a forward axial direction.

4. A ventilating apparatus comprising a 85 substantially rectangular casing having its front face open and having an air-inlet opening in its rear face, a rotatable fan located within said casing and adapted to force air in an axial direction, arcuately 90 curved plates disposed across the corners of said casing, forming pockets in said corners and a substantially cylindrical fan inclosing chamber, passages leading from said chamber to said pockets, and air-conducting 95 receptacles located without said casing and in open communication with said pockets, whereby air received in said pockets is directed forward in an axial direction.

5. In a ventilating apparatus, a rotatable 100 shaft; a fan mounted on said shaft, said fan comprising a plurality of semi-circular blades disposed in upright radial position with respect to said shaft and having their straight chord-like edges diagonally crossing said shaft and extending approximately equal distances on opposite sides thereof; a casing inclosing the periphery of said fan and having its front face open for the free delivery of air from the fan in an axial 110 direction; a central air-intake opening in the rear face of said casing and concentric with said fan; a plurality of passages leading through the side walls of said casing, and means whereby air forced through said 115 passages is directed forward in said axial direction.

6. In a ventilating apparatus, a rotatable shaft; a fan mounted on said shaft, said fan comprising a plurality of semi-circular 120 blades disposed in upright radial position with respect to said shaft and having their straight chord-like edges diagonally crossing said shaft and extending approximately equal distances on opposite sides thereof, 125 transverse blades disposed between adja-

cent diagonal blades adjacent to the outer ends of the latter; a casing inclosing the periphery of said fan and having its front face open for the free delivery of air from the fan in an axial direction; a central air-intake opening in the rear face of said casing and concentric with said fan; a plurality of passages leading through the side walls of said casing, and means whereby air

forced through said passages is delivered in 10 the direction of the direct delivery of air from the fan.

In testimony whereof, I affix my signature in presence of two subscribing witnesses.

WILLIAM D. SCOTT.
